UNITED STATES PATENT OFFICE.

MARTIN SEIDEL, OF WEEHAWKEN, NEW JERSEY, ASSIGNOR TO WEST SHORE
EMBROIDERY COMPANY, OF WEST NEW YORK, NEW JERSEY, A CORPOR-ATION OF NEW JERSEY.

DESIGN FOR LACE.

55,713.

Specification for Design.

Patented July 6, 1920.

Application filed December 30, 1919. Serial No. 348,486. Term of patent 3½ years.

To all whom it may concern:

Be it known that I, MARTIN SEIDEL, a citizen of the German Republic, and a resident of Weehawken, county of Hudson, and State of New Jersey, have invented a new, original, and ornamental Design for Lace, of which the following is a specification, reference being had to the accompanying drawing, forming a part thereof.

The single figure represents a length of lace embodying my design.

I claim:

The ornamental design for lace, as shown.

In testimony whereof I have signed my name to this specification this 14th day of April, 1920.

MARTIN SEIDEL.
